UNITED STATES PATENT OFFICE.

GEORGE R. KELTIE, OF WOONSOCKET, RHODE ISLAND, ASSIGNOR TO THE AMERICAN WRINGER COMPANY, A CORPORATION OF RHODE ISLAND.

WRINGER.

Application filed December 29, 1921. Serial No. 525,647.

To all whom it may concern:

Be it known that I, GEORGE R. KELTIE, a citizen of the United States, residing at Woonsocket, in the county of Providence and State of Rhode Island, have invented certain new and useful Improvements in Wringers, of which the following is a specification.

My invention relates to both power and manually driven wringers, and is more particularly directed to the safety device embodied therein wherein the rolls may in case of emergency be released.

The essential objects of my invention are certainty and speed of release of the rolls; the employment of a minimum number of parts auxiliary to the standard wringer structure; the avoidance of the use of jointed or sectional bars for releasing purposes whereby the structure is weakened; and the attainment of these results in a simple, self contained, and inexpensive structure.

Other objects and advantages of the invention will be apparent as it is better understood from the following description when considered in connection with the accompanying drawings illustrating a preferred embodiment thereof.

To the above ends primarily my invention consists in such parts and in such combinations of parts as fall within the scope of the appended claims.

In the accompanying drawing which forms a part of this specification, Figures 1 and 2 are a front and side elevation respectively of a wringer embodying my invention.

Figure 3, a section of the same on line 3-3 of Figure 1, in locked position, Figure 4, a fragmentary section on line 3-3, in released position,

Figures 5 and 6, longitudinal central sections of the wringer in locked and released positions respectively,

Figure 7, a horizontal section on line 7-7 of Figure 5, and

Figure 8, a plan view of a reclining spring.

Like reference characters indicate like parts throughout the views.

In the construction illustrated the frame comprises side bars 11 provided with the usual guide slots 12 and vertical grooves 13; a top or crossbar 15 in which are incorporated in this instance threaded bushings

16 for the pressure screws 17; housing strips 19 fast to the side bars; bars 22 also fast to the side bars having clothes guide shoudered portions 23; and a drain plate or apron 25 pivoted by pins 27, carried by the side bars, extending into oblong bayonet slots 29. Buttons 31 pivoted to the bars 22 clamp the apron in final position.

In this instance a housing 35 fast to one of the side bars covers the gearing; and angular reinforcing plates 37 fast to the side bars and overlapping the ends of the top bar are employed. The latter are perforated as at 39 to admit the presser screws.

Lower and upper pressure rolls 41 and 42 have their respective shafts 43 and 44 extending through the slots 12 in the side bars, and respectively carry the intermeshing gears 46 and 47 driven by the main shaft 43 in any usual convenient manner. The latter shaft rests on bearing blocks 49 in the lower ends of the slots 12, while the driven shaft 44 has resting thereon bearing blocks 51. In this instance guard plates 53 fast in the end bars by screws 54 have inwardly directed flanges 56 enclosing the ends of the rolls.

Fast to the top of each of the superposed bearings 51 by screws 58 or otherwise is a hinge plate 59 having upon its inner edge hinge sleeves 60 carrying a pintle 61 in hinge sleeves 62 on the corresponding edge of a hinge plate 64 integral with or fast to a pressure spring 66. Integral with or fast to the upper end of each spring is a cam block 68 having upon its upper part an outwardly and downwardly directed inclined cam face 69 engageable with the end of the adjacent pressure screw 17. The descent of the screw upon the cam face 69 combines with the stored up energy of the spring to impel the cam inwardly.

The impulsion of the cams 68 is normally checked by the following device.

A rock shaft 71 is supported in metal straps 72 fast by screws 73 or otherwise to the crossbar 15. Upon the ends of the bar are fingers 75 disposed at right angles thereto and parallel with each other. The central portion of the rock shaft has a depending loop or double crank 77. A handle for the crank in this instance comprises an open or incomplete ring 79 loosely surrounding the crossbar 15 and provided with lateral ears or flanges 81 upon its ends. The ring at a

point opposite its open portion 82 is fast to the crank 77 by rivets 84 or otherwise. Normally the fingers 75 abut against the inner faces of the cams 68. The manual rotation 5 of the handle by pressing an ear 81 in either direction removes the fingers from the cams, and the latter are forcibly impelled together with the springs 66 inwardly and downwardly where they rest on the presser roll 10 42. This action frees the latter roll in case of emergency.

Referring more particularly to the drain plate, the body 25 has lateral flanges 83 equidistant the ends of each of which is the horizontal slot or opening 29 terminating at both ends in extensions thereof or recesses 85 disposed at right angles thereto. It will be observed that when a pin 27 registers in one of the recesses 85 the drain plate is locked 20 against the movement of the latter in the direction of its inclination.

It is to be understood that the invention is not limited to the specific form herein illustrated and described, but may be embodied 25 in other forms without departure from its spirit as defined by the following claims.

I claim:—

1. In a wringer, pressure rolls, bearings 30 slidably supported by the rolls, tilttable compression springs pivotally supported on the bearings, cams on the springs, screws in alignment with the springs and engaging the cams for compressing the springs, and means engageable with the cams for normally retaining them in operative position and operable for releasing the cams and allowing the springs to move on their pivots into a horizontal position.

2. In a wringer, rolls, bearings supported 40 thereby, plates on the bearings, plates on the first plates, hinges connecting the first and second plates, springs upon the second plates, cams fast to the springs, means en-

gaging the cams for compressing the springs and aiding to force them to suddenly move on their pivots when released, and auxiliary means engaging the cams for maintaining the springs against such movement. 45

3. In a wringer, rolls, slidable bearings therefor, vertically disposed springs pivotally connected with the bearings and supported thereby, cams on the springs, pressure screws engaging the tops of the cams, a rock shaft, fingers on the shaft engaging 50 the sides of the cams, and means for operating the rock shaft.

4. In a wringer, rolls, slidable bearings thereon, springs supported on the bearings, cams on the tops of the springs, pressure 55 screws engaging the top faces of the cams, a rock shaft, fingers on the shaft engageable with the cams, a crank on the shaft, and an operating arm on the crank.

5. In a wringer, rolls, bearings thereon, 60 springs supported by said bearings, cams affixed to said springs, pressure screws bearing on said cams, and retaining means for said springs and cams releasable to permit sudden movement of the cams and springs 65 out of complete engagement with said screws. 70

6. In a wringer, rolls, bearings thereon, 75 springs pivotally supported by said bearings for bodily movement toward each other when not restrained, cams having outwardly inclined surfaces, pressure screws bearing on said cams, and retaining means for holding said cams and springs in operative position and releasable to permit the springs to 80 suddenly move toward each other out of complete engagement with said screws.

In testimony whereof I have affixed my signature.

GEORGE R. KELTIE.
